UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING-MACHINE.

1,392,975.

Specification of Letters Patent. Patented Oct. 11, 1921.

Application filed March 4, 1918. Serial No. 320,124.

To all whom it may concern:

Be it known that I, BURNHAM C. STICKNEY, a citizen of the United States, residing in Elizabeth, in the county of Union and State of New Jersey, have invented certain new and useful Improvements in Typewriting-Machines, of which the following is a specification.

This invention relates to typewriting machines of the front-strike variety, and particularly to means for rendering it convenient to make erasures while the work is retained in the machine. It is herein disclosed as applied to an Underwood typewriting machine.

In this class of machines, the typing is done at a point on the work which is so close to the ribbon-vibrating mechanism and the type-guide, and other devices, that it is inconvenient to make erasures. Moreover, owing to the fact that the erasure usually is made so close to the ribbon-vibrating mechanism, and just above it, the detritus is apt to fall onto and clog the mechanism.

The principal object of this invention is to render it practicable and convenient to shift the work away from the ribbon guide, front scale, etc., to a position more convenient for erasing purposes, and then to restore the work to the position from which it was shifted. In the form of the invention herein illustrated, the work is moved upwardly, so that the line of writing is brought temporarily toward the top of the platen, where it may be held mechanically during the operation of erasing, and then restored by being shifted downwardly to bring the printing line to the front of the platen, to proceed with the typing.

This moving upwardly and downwardly of the work is effected by a rotation of the platen itself, this rotation being effected by a single stroke in each direction, a special handle, distinct from the ordinary line-space-driver, being advantageously employed for this purpose, said handle being adapted to give the platen a stroke of identical predetermined length in each direction, so that, upon the return stroke, the work will be brought exactly to its former position.

To avoid liability of objection arising from the running of the feed-rolls over the

work during the shifting of the work up and down, for the described purpose, said rolls may be automatically cast off from the platen, preparatory to effecting the shift of the work. Hence, when manifolding, there is no danger of the carbon being offset onto any of the work-sheets, by reason of the repeated running of the rolls thereover.

Since it is necessary for the work to accompany the platen in the described lifting revolution thereof, there may be provided a device to clip the work temporarily to the platen, and this device or clip is advantageously brought automatically into operation just before the usual feed-rolls are cast off, so that the work is held to the platen by the clip during the entire shifting in both directions, whereupon the rolls are automatically restored, and the clip is automatically released.

Provision is preferably made for avoiding the noise and resistance to free movement that would occur during the rotation of the platen arising from the usual line-space-spring-check or detent. This detent therefore may be made to accompany the platen in its rotation to and fro.

In the present disclosure, the mechanism is for the sake of illustration shown as advancing a work-sheet some three line-spaces, being shown in a form adapted to be used in many of the types of the Underwood typewriting machine now on the market, with practically no change of the principal parts. To increase the throw of the platen, so as to bring the writing line to the top side of the platen, requires only a re-proportioning of parts, longer strokes, and a re-timing of cams. It will be apparent to those skilled in the art that the structure herein shown may be adapted to suit other machines also, and that the mechanism may be caused to impart any desired throw to the platen, by varying the proportions of parts.

Other features and advantages will hereinafter appear.

In the accompanying drawings, Figure 1 is an end view of an Underwood typewriter carriage, showing the present invention as applied thereto, the parts being in ordinary writing position.

Fig. 2 is a similar view, showing the eras-

ing-mechanism handle, moved through a sufficient distance to render the clip effective, and about to cast off the feed-rolls.

Fig. 3 is a similar view, showing the erasing-mechanism-handle at the limit of its throw, having advanced the work-sheet and the platen.

Fig. 4 is a skeleton perspective view of my invention.

Fig. 5 is a front view of the parts as seen in Fig. 1, much of the carriage being broken away.

The work-sheet or sheets 1 are introduced, in the usual way, between the platen 2 and the forward and rear feed-rolls 3 and 4 which run upon the under side thereof, said feed-rolls being controlled by the usual release-key 4^a, whereby they may be cast off, at will, through rotation of the usual shaft 5, for convenience in inserting the sheets. The platen is line-spaced in the usual manner by means of a handle or driver 6, which operates a slide 7 carrying a pawl 8 to engage and drive the ratchet-wheel or line-space wheel 9, which is fixed to the platen axle 10; the platen being held against accidental displacement by means of a detent roll 11, which engages the notches in the line-space wheel 9, and is mounted upon a pivoted detent arm 12 having a spring 13 to press the roll 11 into the notches, and thereby control the platen.

When it is desired to shift the work to a position convenient for making erasures, there is brought into use a shifter, having an arm 14 whereby it may be manipulated and pivoted concentrically with the platen, and capable of giving the platen an advance revolution to bring the writing line higher up on the platen. This shifter is normally disconnected from the platen, and is normally held against movement by means of a bolt or a lock, which is releasable by means of a finger-piece 15. The finger-piece 15 may be pivoted on the arm 14 and comprises an arm 16 having a locking bolt 17 to engage a slot 18 formed in the framework of the platen frame, which is usually a part of the Underwood typewriting machine. By lifting the finger-piece against the tension of the spring 19, which normally holds it effective, this bolt 17 is withdrawn and the platen-positioning arm 14 may be turned upon the axle 10, said arm having a finger-hold 20, whereby it may be operated, and this finger-hold 20 being preferably close to the releasing finger-piece 15, so that it may be grasped by a thumb and a finger, whereby the arm will become almost automatically released by grasping the device for the purpose of rotating the arm.

During the initial part of the stroke of the arm 14, and before the platen is rotated thereby, there is moved against the platen a paper-clip or other work-sheet-holding de-

vice which may comprise, for example, a cross-bar 21 forming part of a bail having arms 22 supported on the axle 10, Figs. 1 and 4. The cross-bar or work-sheet-holder extends longitudinally of the platen and stands normally below or away from the platen in notches 23 formed in the bottom paper-apron, Fig. 4, which is usually provided for the platen of an Underwood machine. The clip-bar 21 may be operated by an arm 24 having a roll 24^a to run upon a double-cam 25, which is formed by a slot upon said positioning arm, this cam including a comparatively steep portion 26 to cause the first movement of the arm to bring the clip into action, Fig. 2. To do this, the arm 24 rocks a stub-shaft 26^a having at its inner end an upwardly-projecting arm 26^b, to swing the latter and cause a pin 26^c, projecting through a slot in the platen frame, to raise the clip to its effective position by engaging in a cam-slot 36^a formed in the arm 22 of said clip. The cam also comprises a dwell 27 so that the clip 21 will remain in effective position during the remainder of the stroke of the arm 14 to the Fig. 3 position, and also during almost all of the early part of the return stroke of the arm 14, so that the paper is securely kept to the platen during the entire advance and return strokes thereof.

As soon as the paper has been clipped, the device comes into play for casting off the feed-rolls from the platen. For this purpose, the usual feed-roll-release shaft 5, which is connected to the roll-release key, aforesaid, is provided with an arm 28 having a roll 29 to run upon a second cam 30 which is provided on said platen-rotating arm 14. This second cam includes a steep portion 31 adapted to cause the release shaft 5 to become effective as soon as the paper-clipping action of the first cam 25 is completed, Fig. 2. When the roll runs upon the second cam 30, the releasing shaft 5 is rocked, and the usual cams 32, which are provided thereon, Figs. 3 and 5, operate to swing the releasing arms which are formed upon the usual roll-carrying arms. The releasing cam 30 terminates in a dwell 33, along which the roll 29 runs during the remainder of the stroke of the arm, whereby the feed-rolls are held off from the platen during the entire advance and return strokes thereof.

The operations of clipping the paper to the platen and releasing the feed-rolls are performed by said arm 14 as a preliminary to rotating the platen, and the rotation is then effected preferably by means of a frame 34, which is also pivoted concentrically with the platen on the platen axle, and is connected to drive the platen, this connection consisting of the detent 12, which has already been described. The frame comprises an arm 35, to which said detent is pivoted.

During the preliminary movement of the arm 14, the frame 34 is held by a spring 34^a, thus permitting the actuation of the clip and the releasing of the feed-rolls. After the 5 releasing of the feed-rolls, the end of the cam-slot 25 is reached by the roll 24^a. Thus, during the final portion of the stroke of the arm, said frame is rocked, the stub-shaft 26^a being carried thereby, and by means of the 10 detent drives the ratchet-wheel, which is fixed to the platen axle, whereby the platen is rotated, until the arm 14 is arrested by a stop 37; whereupon the spring 19 projects the locking bolt into a second slot 39, Figs. 15 1 and 3, which is formed upon the platen frame aforesaid, so that the platen is locked in this position, convenient for erasure, and where the detritus is not apt to drop into the ribbon mechanism.

20 To effect an equally distributed pressure of the clip against the work-sheet around the platen, I have duplicated, on the right-hand side of the platen, the mechanism for actuating said clip, so that it is moved parallel to itself; said mechanism comprising 25 an actuating element 45 which is moved simultaneously with the arm 14.

To move the element 45 simultaneously with the arm 14, I have provided a connection between them. This may comprise a 30 rock shaft 46 supported by brackets 47 on the platen frame, movement being imparted to said rock shaft from said arm 14 through the intermediary of a pin 48 projecting from said arm into a slot 49 formed in the free end of an arm 50, which is secured at the left-hand end of said shaft. The right-hand end of said rock shaft 46 is provided with a similar arm 51 engaging with a pin 52 projecting from the element 45. Thus, the 35 movement is transferred from said rock shaft to said element, and said element is moved simultaneously with said arm 14. The frame 34 comprises also a tie-rod 41 connecting the arm 35 to a similar arm 35^a, each of these arms having extensions 42 extending past the platen axle, and said arms carrying at their lower ends the stub-shafts 26^a (Fig. 4).

40 The extensions 42 are also provided with pins 53 projecting into slots 54 formed in the arms 22 of the clip 21 to guide the latter in its movements to and away from the platen. It will be seen that the pins project through 45 slots 55 formed in the arms 26^a. This is to permit a movement of said arms to render said clip effective before the frame 34 is moved by the arm 14, as hereinbefore described.

45 As soon as the erasure is completed, the operator again grasps the finger-piece 15, releasing the platen-driving arm 14, and then swings said arm upwardly to a normal position, during which operation the platen rotates 50 backwardly, the paper being held by

the clip 21 until the platen is returned to initial position, whereupon a stop 43, in the path of the detent arm 35, arrests said arm, together with said detent 11, 12 and the ratchet-wheel and platen.

70 During the completion of the return movement of the platen-rotating arm 14, the roll 29 runs down the cam 31 upon said arm, to permit the shaft 5 to rock and permit the feed-rolls 3 and 4 to be restored to 75 the platen by the usual return springs, and then the roll 24^a is positively moved by the first cam 25, to withdraw the paper-clip from the platen. Upon releasing the device, the spring 19 restores the locking bolt 17, so 80 that the platen-rotating arm is held against displacement. Said locking bolt holds said arm steady during the normal operation of the machine, so that it affords a satisfactory anchorage for the detent 12 which holds the 85 platen steady during the typing operation.

85 While the invention has been described as applied to an erasing device, certain elements and sub-combinations of the mechanism may be used for other purposes and in 90 other combinations.

Variations may be resorted to within the scope of the invention.

Having thus described my invention, I claim:

95 1. In a typewriter, in combination, a revoluble platen, mechanism normally in effective relation to cooperate therewith as means to feed work-sheets thereabout, a normally ineffective work-sheet-holder, and a common operating device for said holder and feeding means, comprising means to render said holder effective to clamp said sheets against said platen, means to render said feeding means ineffective, and means to rotate said holder and platen with said sheets clamped firmly therebetween.

100 2. In a typewriting machine, the combination with a revoluble platen, of feeding devices adapted to hold a work-sheet upon said platen to cause it to move with the revolving platen, other feeding devices adapted to grip the work-sheet to said platen, a finger-piece movable to free the first-mentioned feeding devices from the 105 platen and to cause said other feeding devices to grip the platen and rotate therewith to carry the work-sheet around the platen, a line-space mechanism for said platen including a detent and a wheel, and means 110 whereby said detent turns said wheel to revolve the platen.

115 3. In a typewriter, in combination, a revoluble platen mechanism comprising feed-rolls normally in effective relation with said platen to cooperate therewith as means to feed worksheets thereabout, a normally ineffective work-sheet-holder, and a common operating device for said holder and feeding means, comprising means to render said 120 platen

holder effective to clamp said sheets against said platen, means to move said feed-rolls away from said platen to render said feeding means ineffective, and means to rotate 5 said holder and platen with said sheets clamped firmly therebetween.

4. In a typewriter, in combination, a revoluble platen, mechanism normally in effective relation to coöperate therewith as 10 means to feed work-sheets thereabout, a normally ineffective work-sheet-holder, and a common operating device for said holder and feeding means, comprising means to render said holder effective to clamp said 15 sheets against said platen, means to render said feeding means ineffective, and means to impart an advance rotation to said holder and platen with said sheets clamped firmly therebetween, said operating device also affording means to restore said holder, platen and the work-sheets clamped therebetween to the positions from which they were advanced, to permit said feeding means to again become effective, and to render said 20 holder ineffective.

5. In a typewriter, in combination, a revoluble platen, mechanism normally in effective relation to coöperate therewith as 25 means to feed work-sheets thereabout, a normally ineffective work-sheet-holder, and a common operating device for said holder and feeding means, comprising means to render said holder effective to clamp said sheets against said platen, and means to 30 render said feeding means ineffective; said platen and holder, with said sheets clamped therebetween, being free to be rotated together, said sheets being free from said feeding means during such rotation.

40 6. In a typewriting machine, in combination, a platen frame, a platen, an axle on which said platen is mounted in said frame, mechanism comprising feed-rolls normally in effective relation with said platen to co- 45 operate therewith as means to feed work-sheets thereabout, a normally ineffective paper-holder shiftably mounted on said axle, a swinging frame mounted on said axle, means mounted in said frame for shifting 50 said paper-holder into effective paper-clamping relation with said platen, and a common operating mechanism for said feeding means and paper-holder, said operating mechanism comprising means to so operate said shifting 55 means as to render said paper-holder effective, means to move said feed-rolls away from said platen, so as to render said feeding means ineffective, and means to effect a rotation of said platen, paper-holder, 60 swinging frame and shifting means about said axle independently of said feeding means.

7. In a typewriting machine, the combination with a revoluble platen, of feed-rolls 65 adapted to hold a work-sheet against said

platen, a casting-off element for said feed-rolls, a normally ineffective work-sheet-holding device adjacent said platen, connections to said device, a frame on which said connections are mounted, an axle for 70 said platen on which said frame is journaled, a finger-piece adapted to be moved to cast off said feed-rolls and to cause said device to clamp the work-sheet to said platen, and connections whereby said finger-piece there- 75 after causes the platen to rotate with said device, said connections including an extension of said frame, a line-space wheel for said platen, and a detent pivoted on said frame adapted to bear against said line- 80 space wheel.

8. In a typewriting machine, the combination with a revoluble platen, of feed-rolls adapted to hold a work-sheet against said platen, a casting-off element for said feed-rolls, a normally ineffective work-sheet-holding device adjacent said platen, connections for said device, a frame on which said connections are mounted, an axle for said platen on which said frame is journaled, a finger- 85 piece adapted to be moved to cast off said feed-rolls and to cause said device to clamp the work-sheet to said platen through said connections, other connections whereby said finger-piece thereafter causes the platen to 90 rotate with said device, and means normally holding said finger-piece ineffective and adapted to be set to cause said finger-piece to remain effective.

9. In a typewriting machine, the combination with a revoluble platen, of feed-rolls adapted to hold a work-sheet against said platen, a casting-off element for said feed-rolls, a normally ineffective work-sheet-holding device adjacent said platen, connections for said device, a frame on which said connections are mounted, an axle for said platen on which said frame is journaled, a finger-piece adapted to be moved to cast off said feed-rolls and to cause said device to clamp the work-sheet to said platen through said connections, other connections whereby said finger-piece thereafter causes the platen to 95 rotate with said device, and means normally holding said finger-piece ineffective and adapted to be set to cause said finger-piece to remain effective.

10. In a typewriting machine, the combination with a revoluble platen, of feed-rolls adapted to hold a work-sheet against said platen, a casting-off device for said feed-rolls, a work-sheet-holding-device adapted to clamp the work-sheet against said platen, a finger-piece operable to make said holding device effective, an axle for said platen on which said finger-piece is pivoted, 125 110 115 120 125 130

a cam by which said finger-piece operates platen but normally ineffective and extending through depressions in said apron, a finger-piece normally holding said device ineffective but adapted to be moved to grip the platen to hold a work-sheet thereagainst, so 70
5 work-holding-device effective.

11. In a typewriting machine, the combination with a revoluble platen, of feed-rolls adapted to hold a work-sheet against said platen, a casting-off device for said feed 10 rolls, a work-sheet-holding-device adapted to clamp the work-sheet against said platen, a finger-piece operable to make said holding-device effective, an axle for said platen on which said finger-piece is pivoted, a cam by 15 which said finger-piece operates said work-holding-device, a second cam adapted to make said casting-off device effective after said first-named cam has made the work-holding-device effective, a frame on which 20 said work-holding-device is journaled, an axle for said platen on which said frame is journaled, a detent device for said platen on said frame, and a lost-motion connection between said finger-piece and said frame to 25 move the platen after the work-holding-device has become effective.

12. In a typewriting machine, the combination with a revoluble platen, of feed-rolls adapted to hold a work-sheet against said platen, a casting-off device for said feed - rolls, a work - sheet - holding - device adapted to clamp the work-sheet against said platen, a finger-piece operable to make said holding-device effective, an axle for said 30 platen on which said finger-piece is pivoted, a cam by which said finger-piece operates said work-holding-device, a cam adapted to make said casting-off device effective after said first-named cam has made the work- 35 holding-device effective, a frame on which said work-holding-device is journaled, a detent device for said platen on said frame, a lost-motion connection between said finger-piece and said frame to move the platen 40 after the work-holding-device has become effective, and means adapted to detain said finger-piece in either its normal position or the position in which it has been moved to move the platen.

50 13. In a typewriting machine, the combination with a revoluble platen and a paper-apron adjacent thereto adapted to curve work-sheets around the platen, of a work-sheet-gripping-device adjacent said platen but normally ineffective and extending through depressions in said apron, and a finger-piece normally holding said device ineffective but adapted to be moved to grip the platen to hold a work-sheet thereagainst, 55 so that it will travel with the platen.

14. In a typewriting machine, the combination with a revoluble platen and a paper-apron adjacent thereto adapted to curve work-sheets around the platen, of a 60 work-sheet-gripping-device adjacent said

through depressions in said apron, a finger-piece normally holding said device ineffective but adapted to be moved to grip the platen to hold a work-sheet thereagainst, so 70 that it will travel with the platen, feed-rolls extending through said apron, a casting-off element for said feed-rolls, and means for casting off said feed-rolls by the operation of said finger-piece after it has made the device 75 effective.

15. In a typewriting machine, the combination with a revoluble platen and a paper-apron adjacent thereto adapted to curve work-sheets around the platen, of a work- 80 sheet-gripping device adjacent said platen but normally ineffective and extending through depressions in said apron, a finger-piece normally holding said device ineffective but adapted to be moved to grip the 85 platen to hold a work-sheet thereagainst, so that it will travel with the platen, feed-rolls extending through said apron, a casting-off element for said feed-rolls, means for casting off said feed-rolls by the operation 90 of said finger-piece after it has made the device effective, and connections whereby the finger-piece, on its further movement, causes the platen and device to rotate together.

95 16. In a typewriting machine, the combination with a revoluble platen and an apron for curving a work-sheet therearound, of a device extending within openings in said apron and adapted to be moved against the 100 platen to grip the work-sheet thereto, an axle for said platen, a frame journaled on said axle, actuating means on said frame, and a finger-piece adapted to move said device clear of the apron and against said 105 platen through the intermediary of said actuating means, so that the platen and device will rotate together.

17. In a typewriting machine, the combination with a revoluble platen and an apron 110 for curving a work-sheet therearound, of a device extending along and within openings in said apron and adapted to be moved against the platen to grip the work-sheet thereto, an axle for said platen, said device 115 being mounted on said platen axle, a frame being journaled on said axle, actuating means on said frame, a finger-piece adapted to move said device clear of the apron and against said platen through the intermediary 120 of said actuating means, so that the platen and device will rotate together, a detent for said platen, and an extension of said frame on which said detent is mounted.

18. In a typewriting machine, the combination with a revoluble platen and a paper-apron adapted to curve a work-sheet there-around, of a device near said platen and extending throughout its length, but normally 125 ineffective, and lying within openings in 130

1. In a typewriting machine, the combination with a revoluble platen and a paper-apron adapted to curve a work-sheet there-around, of a device near said platen but normally ineffective, a rod on which said device is mounted, a finger-piece adapted to move said device to cause it to bear against the platen, and connections whereby, after said device bears against the platen, the platen and device move together. 5
2. In a typewriting machine, the combination with a revoluble platen and a paper-apron adapted to curve a work-sheet there-around, of a device near said platen but normally ineffective, a rod on which said device is mounted, a finger-piece adapted to move said device to cause it to bear against the platen, connections whereby, after said device bears against the platen, the platen and device move together, a frame journaled on said rod and carrying intermediate actuating means for said device, feed-rolls for 10 said platen, and a cam fast to said finger-piece adapted to cast off said feed-rolls after moving said device against the platen. 15
3. In a typewriting machine, the combination with a revoluble platen, of feed-rolls adapted to hold a work-sheet against said platen, a casting-off device for said feed-rolls, a normally ineffective device adjacent said platen, an axle for said platen on which said device is journaled, a finger-piece adapted to be moved to cast off said feed-rolls and to cause said device to clamp the work-sheet to said platen, and connections whereby said finger-piece thereafter causes the platen to rotate with said device 20 first in one direction and then in the other. 25
4. In a typewriting machine, the combination with a revoluble platen, of feeding devices adapted to hold a work-sheet upon said platen to cause it to move with the revolving platen, other feeding devices adapted to grip the work-sheet to said platen, a finger-piece movable to free the first-mentioned feeding devices from the platen and to cause said other feeding devices to grip 30 the platen and rotate therewith to carry the work-sheet around the platen, a line-space mechanism for said platen including a detent and a wheel, and means whereby said detent turns said wheel to revolve the platen first in one direction and then in the other. 35
5. In a typewriting machine, the combination with a revoluble platen and feed-rolls adapted to hold a work-sheet against said platen, of devices for casting off said feed-rolls, a device adapted to be clamped to said platen to hold the work-sheet to said platen and to travel therewith, and a finger-piece adapted to clamp said device against said platen and then to make said casting-off devices effective, and then to rotate said platen with said clamping device to carry the work-sheet to a new position first in one direction and then in the other. 45
6. In a front-strike typewriting machine, the combination with a revoluble platen, of a manually-operable device for rotating said platen forwardly and backwardly, and a normally ineffective work-clip movable by said manually-operable device against said platen to carry the work around with the 50 platen. 70
7. In a front-strike typewriting machine, the combination with a revoluble platen, of a manually-operable device for rotating said platen forwardly and backwardly, a normally ineffective work-clip movable by said manually-operable device against said platen to carry the work around with the platen, and means independent of said work-clip for normally coöperating with the 75 platen to feed the work around the same. 80
8. In a front-strike typewriting machine, the combination with a revoluble platen, of a manually-operable device for rotating said platen forwardly and backwardly, a normally ineffective work-clip movable by said manually-operable device against said platen to carry the work around with the platen, means independent of said work-clip for normally coöperating with the platen to feed the work around the same, and means 85 also controlled by said manually-operable device for releasing said normally effective work-feeding means concomitantly with the movement of said clip to the platen. 90
9. The combination with a revoluble platen and a roll to run thereon, of a work-clip, a manually-operable device to rotate the platen forwardly and backwardly, and means to enable said manually-operable device first to move said clip against the platen, and then to release said roll and rotate said platen. 100
10. The combination with a revoluble platen, of a normally ineffective clip for holding the work to the platen, a manually-operable device, means controlled by said manually-operable device to move said clip against the platen, a feed-roll to run upon the platen, means operable by said manually-operable device for releasing said feed-roll, a ratchet-wheel connected to said platen, a detent engaging said ratchet-wheel, and means to enable said manually-operable device to advance and return said 105 platen by means of said detent. 110
11. The combination of a revoluble platen, a work-clip normally ineffective, a manually-operable device, a cam to enable said manually-operable device to move said work-clip against the platen, a frame mounted to swing about the platen axis, said work-clip being controlled by means mounted upon said frame so as to travel therewith during the rotation of the platen forwardly and backwardly, a feed-roll to run upon the platen, a second cam operable by said manually-operable device to release said feed-roll, a line-space wheel connected to said platen, a detent upon said frame to 120 125 enable said manually-operable device to move said work-clip against the platen. 130

gage said line-space wheel, and means effective after the clipping of the work and the release of said feed-roll, for enabling said manually-operable device to swing said frame, and thereby drive the line-space wheel and platen.

29. The combination with a platen having a printing point at the front thereof and around which a work-sheet may be fed, of 10 feed-rolls normally holding said work-sheet against said platen, means for changing the position of the work-sheet relatively to the printing point, said feed-rolls being rendered ineffective during the changing of the 15 position of said work-sheet, a platen axle, a clamping bar extending lengthwise of said platen and supported on said platen axle, and means for actuating said clamping bar to hold said work-sheet before said feed-rolls are rendered ineffective.

30. The combination with a platen having a printing point at the front thereof and around which a work-sheet may be fed, of feed-rolls normally holding said work-sheet 25 against said platen, means for changing the position of the work-sheet relatively to the printing point, said feed-rolls being rendered ineffective when changing the position of said work-sheet, a platen axle, a 30 clamping bar extending lengthwise of said platen and supported on said platen axle, means for actuating said clamping bar to hold said work-sheet before said rolls are rendered ineffective, and means for rotating 35 said platen with said clamping bar after the feed-rolls have been rendered ineffective.

31. In a typewriting machine, in combination, a platen, a normally ineffective paper-holder extending from end to end thereof, and an operating mechanism for moving 40 said holder into clamping relation with said platen, said mechanism comprising a pair of actuating devices, one adjacent each end, means connecting said devices so as to cause 45 them to operate in synchronism, and an operating finger carried by one of the devices of said operating mechanism.

32. The combination with a platen having a printing point at the front thereof and 50 around which a work-sheet may be fed, of a normally ineffective device adjacent to said platen and extending from side to side thereof, means at each side of said device to actuate said device to clamp the work-sheet 55 against said platen prior to a displacing movement of said work-sheet relatively to the printing point, said means comprising two actuating elements, one at each side of said device, and means connecting said actuating elements, said connecting means comprising a rock shaft, two arms, one at each 60 end of said rock shaft, each arm extending adjacent to one of the actuating elements, and each arm having a pin-and-slot connection with its associated element.

33. In a typewriting machine, in combination, a platen frame, a platen, an axle on which said platen is mounted in said frame, a normally ineffective paper-holder shiftably mounted on said axle and extending 70 from end to end of said platen, a swinging frame mounted on said axle, a pair of shifting elements mounted in said swinging frame, one for each end of said holder, and an operating mechanism by which said shifting elements may be caused to shift said holder into clamping relation with said platen, and by which said platen, holder and swinging frame may be rotated together 75 about said axle, said operating mechanism comprising a pair of actuating devices, one for each shifting element, means mounted in said platen frame and connecting said devices so as to cause them to operate in synchronism, and an operating finger-piece 80 carried by one of the elements of said operating mechanism.

34. The combination with a platen having a printing point at the front thereof and around which a work-sheet may be fed, of a 90 normally ineffective device adjacent to said platen, a platen axle, said device being supported on said platen axle, a swinging frame supported on said platen axle, actuating elements at each side of said device, a connection between said actuating elements, a finger-piece on one of said actuating elements, connections from said actuating elements to said device, said last-mentioned connections comprising means supported by said swinging frame, the means of each of said connections comprising two arms, a stub shaft upon which said arms are mounted, one of said arms being engaged by a cam on the associated actuating element, the other arm engaging 95 with a cam on said device.

35. The combination with a platen having a printing point at the front thereof and around which a work-sheet may be fed, of a 100 normally ineffective device adjacent to 110 said platen, a platen axle, said device being supported on said platen axle, a swinging frame supported on said platen axle, actuating elements at each side of said device to render said device effective to clamp the 115 work-sheet, a connection between said elements, a finger-piece on one of said actuating elements, connections from said actuating elements to said device, said last-mentioned connections comprising means supported by said swinging frame, and means 120 carried by said swinging frame to guide said device while it is being moved to its clamping position.

36. The combination with a platen having a printing point at the front thereof and around which a work-sheet may be fed, of a 125 normally ineffective device adjacent to said platen, feed-rolls, an actuating element comprising a finger-piece, a swinging frame, 130

a connection comprising mechanism supported by said swinging frame for rendering said device effective by said actuating element, said actuating element being effective to render said feed-rolls ineffective after said device has been rendered effective, means comprising a spring to retain said swinging frame in its normal position until the feed-rolls have been rendered ineffective, 10 and a yielding connection between said

swinging frame and said platen, said actuating element being adapted to move said swinging frame to rotate said platen with said device after the feed-rolls have been rendered effective.

BURNHAM C. STICKNEY.
